UNITED STATES PATENT OFFICE

2,487,160

LIFT DEVICE

Ora R. McColley, Columbus, Mont.

Application July 6, 1945, Serial No. 603,440

1 Claim. (Cl. 254—93)

1

This invention relates to lifting devices, and more particularly to a lift device for lifting and dressing a human body, for lifting and handling caskets, for lifting heavy vaults and the like, and for other heavy lifting tasks as required in a funeral home.

A main object of this invention is to provide a novel and improved lifting device of simple construction and which is adapted to be employed for a wide range of lifting tasks in a funeral home or mortuary.

A further object of the invention is to provide an improved lifting structure which employs hydraulic foot-actuated pump means to provide the lifting effort and which is simple and efficient in operation.

Further objects and advantages of the invention will appear from the following description and claim, and from the accompanying drawings, wherein:

Figure 1 is a front elevational view of a lifting device in accordance with this invention.

Figure 2 is a plan view of the structure of Figure 1.

Figure 3 is an end elevational view of the lifting device of Figure 1.

Figure 4 is a detail view showing the connection of the lift bar to the hydraulically actuated piston jack member employed in the structure of Figure 1.

Figure 5 is a detail view in perspective showing a portion of the lift bar employed in the lifting device of Figure 1.

Figure 6 is a schematic diagram showing the hydraulic system employed in the lifting device of Figure 1.

Referring to the drawings, the lifting device comprises a frame 1 having a rear panel 2 and end panels 3 and 4. The end panels are built up of tubular steel bars welded together to form rectangular frame sections and are each supported on a pair of casters 5, 5. The rear panel 2 comprises a horizontal top tubular bar 6 welded at its ends to the top rear corners of end sections 3 and 4 and a horizontal bottom tubular bar 7 welded at its ends to the lower portions of said end sections. Inclined brace members 8, 8 are employed in rear panel 2 to provide rigidity.

Secured rigidly on each end panel adjacent the forward portion thereof is a vertical cylinder 9, each vertical cylinder having mounted therein an upwardly movable piston 10. The top end of each piston 10 is threadedly secured to a cap member 11, the cap members being welded

to a longitudinally extending flat bar 21. Bolted to cap members 11 through bar 21 is a longitudinal angle bar 12 supported in position with one flange vertical and the other flange horizontal, said horizontal flange being uppermost. Angle bar 12 carries a plurality of longitudinally spaced straps 13 wherein the load to be raised is supported.

Connected to the lower portion of each cylinder 9 is an oil pipe through which oil is forced by a pump 15 when it is desired to raise the pistons 10. The oil pump 15 is actuated by a foot pedal 14 arranged at the rear portion of frame 1. A supply tank 16 for the oil is provided adjacent pump 15, said tank being connected to the pump by an oil admission pipe 17. The outlet side of the pump is connected to the tank by a return pipe 18 having a release valve 19 positioned therein.

Control valves 20, 20 are provided in the hydraulic lines for the respective cylinders 9, 9 to manually control the admission or release of oil to and from the cylinders.

In operation, the load is secured to straps 13, valves 20, 20 are opened, and the operator steps on pedal 14. Pistons 10, 10 are thereby raised by the action of pump 15, lifting the load to a desired elevation. The load may be secured in raised position by closing valves 20, 20. The frame may then be moved on its casters to a desired location. The load may be lowered by opening valves 20, 20 and release valve 19, thereby allowing pistons 10, 10 to descend and returning excess oil to tank 16 through pipe 18. To re-apply lifting force valve 19 is closed.

The oil pipe running longitudinally from the pump 15 to the cylinders at the end frame section 3 is housed in the lower longitudinal tubular bar member 7, as shown in Figures 1 and 2.

While a specific embodiment of a lifting device has been disclosed in the foregoing description, it will be understood that various modifications within the spirit of the invention may occur to those skilled in the art. Therefore, it is intended that no limitations be placed on the invention other than as defined by the scope of the appended claim.

What is claimed is:

In a lift device, a pair of vertical end panels including front and rear ends, a vertical rear panel rigidly connecting said rear ends of said end panels together, said rear panel being relatively longer than said end panels whereby to provide with said end panels a rectangular enclosure entirely open at the bottom and at the

2

front, a vertical hydraulic cylinder fixed to each end panel between said front and rear ends thereof, pistons in said cylinders, each piston including an upper end disposed above said end panels, a crosshead connecting said upper ends of said pistons, spaced cradle-supporting elements on said crosshead, and means for supplying hydraulic fluid under pressure to both of said cylinders simultaneously whereby to elevate said pistons and crosshead. 5

ORA R. McCOLLEY.
